UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES F. B. TOWNE, E. S. TOWNE, J. M. TOWNE, AND F. W. WILSON.

UNITARY TELESCOPING ELEMENT AND LOCKING MEANS.

Application filed September 22, 1923. Serial No. 664,277.

To all whom it may concern:

Be it known that I, JOHN SCHADE, a citizen of the United States, residing at the city of Holyoke, in the county of Hampden and State of Massachusetts, have invented certain new and useful Improvements in Unitary Telescoping Elements and Locking Means; and I do declare the following to be a full, clear, and exact description 10 of the invention, such as will enable others skilled in the art to which it appertains to make and use the same.

This invention relates to unitary telescoping elements and locking means therefor, 15 and has for its object to provide a very simple and effective device of this description, and furthermore, to equip the telescoping elements with locking means which shall be positive and automatically operated 20 by the compression of said elements.

Further objects of the invention will appear from the description to follow supplemented by the accompanying drawing, in which—

25 Figure 1 is a broken plan view illustrating the invention as applied to a loose leaf binder—

Figure 2 is a section at the line 2—2 of Figure 1, the section being taken through 30 the binder elements of the loose leaves only—

Figure 3 is a similar section taken at the line 3—3 of Figure 1—

Figure 4 is a view illustrating the elements of the improvement in detached condition preparatory to assembly—

Figure 5 is a detail broken view partly in section of the inner telescoping element—

Figure 6 is an elevation, partly broken, of the invention in its simplest form, and

40 Figure 7 is a plan view broken away of one of the loose leaves.

Similar numerals of reference denote like parts in the several figures of the drawing.

45 1, 2, are the usual binder elements which may be made of wood or any suitable material each having secured thereto the usual complementary hinge element 3, 4. 5, 6, are respectively the inner and outer telescoping

50 elements, the former having one extremity externally threaded and closed by a plug 7 having a slot 8, the function of which latter will be hereinafter described. The lower

extremity of this inner tube 5 has formed therewith a detent 9.

55 The outer telescoping element 6 has an elongated gate 10 which opens through the outer extremity of such element, one wall of said gate having extending therealong ratchet teeth 11.

12 is a threaded screw cap which is driven on the plug end of the element 5, and 13 is an end cap having prongs 14 extending inwardly therefrom, and also having secured thereto a spindle 15 projecting centrally and 65 inwardly therefrom.

16 is a coil spring which is assembled around the spindle 15 one extremity 17 of the spring being anchored around one prong 14 while the other extremity 18 is anchored 70 within the slot 8 of the plug 7.

In assembling the parts of the improvement the inner element 5 is thrust upwardly through the element 6 until the threaded end of the former element extends beyond the latter element, and the screw cap 12 is then driven on the threaded end. The coil spring 16 is placed within the telescoped members and its extremities anchored in the manner before described.

80 In applying the device to the binder elements 1, 2, the outer telescoping element 6 is first then inserted through the binder elements, and the inner telescoping element 5 inserted through the element 6, and the screw cap 12 driven on the part 5. The spring 16 is then inserted and anchored in the manner before described, and the end cap 13 thrust inwardly to compress the spring, and given one or two turns so as to 85 wind the spring for producing a torsional effect of the latter. When the end cap has been thrust inwardly to completely compress the spring it will be housed within the outer face of one of the binder elements, the element 2 in the present instance, and the prongs 14 will have been thrust beyond the inner face of the binder element and clinched over the same, as more particularly shown 90 at Figure 2 of the drawings.

100 These prongs 14 pass through grooves 19 formed in the element 2 so that the end cap 13 is prevented from turning and the spring thereby held under torsion.

But the end cap can be held within the 105 element 2 and anchored as against turning

in very many ways, all of which are mere mechanical expedients, and the invention is therefore not limited in this respect.

The improvement is not limited to use in connection with any special binder elements since it may be in the form of a separate unit which might lie on a desk or be suspended from a hook, the loose leaves 20 being provided with the usual openings 21 having gate portions 22, as shown at Figure 7, so that the leaves are merely pushed onto the telescoping elements and are readily removed therefrom, and therefore at Figure 6 is shown a construction which might be utilized independent of any binder sections, and in this figure the extremities of the spring are merely anchored to the outer end of the inner element 5 and to a closure cap 23 and the latter given one or more turns 20 to place the spring under tension after which said cap is rigidly crimped to the outer end of the element 6.

In operating the improvement, whether it is used in connection with special binder elements or not, the telescoping members 5, 6, are merely compressed against the sheets contained on these members, and since the detent 9 is always forced toward the ratchet teeth 11 by the torsion of the spring, the engagement of such detent and ratchet will lock the loose sheets in position.

In order to release the sheets the screw cap 12 is turned so as to bring the detent out of the ratchet and the propelling force of the spring will then separate these members 5, 6, and unlock the sheets.

In order to increase the holding capacity of the members 5 and 6, additional threaded sections may be driven on the outer end of the member 5 and the screw cap 12 secured to the outermost section.

What is claimed is:

1. The herein described improvement in telescoping parts for loose leaf sheets, comprising extensible telescoping post elements, one of which carries a ratchet while the other carries a pawl adapted to engage the ratchet, and spring means contained within the posts for normally effecting the engagement of said pawl and ratchet and also permitting the resilient compression of the posts. 45 50

2. A device for holding loose sheets, consisting of hollow telescoping elements, one of which has ratchet teeth thereon and the other a projection for engaging said teeth, and spring means contained within said elements for exerting both a propelling and torsional effect. 55

3. The herein described unitary structure for holding loose leaf sheets, comprising telescoping hollow extensible posts, carrying respectively a ratchet and a detent, and spring means contained within the posts for normally effecting the engagement of said ratchet and detent and for permitting the resilient compression of the posts. 60 65

4. A device for holding loose sheets, comprising two hollow telescoping tubes, the inner one of which is closed at one end and carries a detent at the other end while the outer tube has a slot extending the major portion of the length of the tube, ratchet teeth being formed along one edge of said slot, said detent extending within said slot, 70 75 and a coil spring housed within said tubes and having its extremities anchored, said spring being under torsion whereby said detent and ratchet are always engaged.

In testimony whereof I affix my signature hereto.

JOHN SCHADE.
